[57] CLAIM

The ornamental design for dental X-ray film holder,
substantially as shown and described.

DESCRIPTION

FIG. 1 is a frontal perspective view of the dental X-ray
film holder, showing my new design;

FIG. 2 is a side elevational view thereof, taken from the
left hand side of FIG. 1;

FIG. 3 is a top plan view thereof;

FIG. 4 is a bottom plan view thereof;

FIG. 5 is a front elevational view thereof;

FIG. 6 is a rear elevational view thereof; and

FIG. 7 is a side elevational view thereof, taken from the
right hand side of FIG. 1.
